UNITED STATES PATENT OFFICE

2,675,171

COIN HOLDER

John C. Long, Charleston, S. C.

Application January 2, 1951, Serial No. 203,954

1 Claim. (Cl. 229—92.9)

1
This invention relates to coin holders such as are used for sending coins through the mails and particularly to special structural features of such devices.

There are available several types of coin holders for mailing each involving a different manner of inserting and/or holding the coin in a recess or pocket in a cardboard sheet. A difficulty with many of these devices is that they have no means except friction for holding the coins in the card, and those which provide special holding means are relatively expensive to manufacture.

The present invention provides a novel coin and currency holder which is of relatively simple but unique construction, which positively holds coins in place and conceals them from being detected by handling the envelope, thereby reducing the chances of theft, and satisfies all mailing requirements.

The major object of the invention is therefore to provide a novel coin holder of simple construction that is easy and inexpensive to manufacture and very easy to use.

A further object of the invention is to provide a coin holder wherein a sheet of cardboard or the like is folded upon itself with an end section formed with coin holding recesses and enclosed between an intermediate section and the other end section.

It is a further object of the invention to provide a coin holder of cardboard or the like having a novel recessed body and closure flap arrangement.

Further objects of the invention will appear in connection with the appended claim and the annexed drawings wherein:

Figure 1 is a top plan view of a closed coin holder of the invention;

Figure 2 is a top plan view of the coin holder with the closure flap open;

Figure 3 is an enlarged section on line 3—3 of Figure 1; and

Figure 4 is an enlarged section on line 4—4 of Figure 2.

My novel coin holder is made entirely from a single rectangular sheet of stiff cardboard, fibreboard or the like which is folded twice like a business letter and comprises an end section 11, an intermediate section 12 and another end section 13 all of about the same size. Intermediate section 12 is folded down to underlie end section 11, the fold line or bend being indicated at 14. Opposite bend 14 is a reverse bend 15 around the free edge of end section 11, and end section 13 is folded down to overlie end section 11. Thus,

2
in the assembly, end section 11 has full surface contact, above and below, with end section 13 and intermediate section 12 respectively.

End section 11 is formed with a series of coin receiving apertures 16 preferably of diameters to snugly receive dimes, pennies, nickels, quarters and half dollars. In the assembly the bottom surface of end section 11 is tightly and permanently glued or similarly secured to the entire top surface of intermediate section 12, so that the portions of intermediate section 12 visible through the apertures 16 function as bottom walls to convert apertures 16 into pockets.

Preferably the thickness of the cardboard is that of a fifty cent piece, or it may be as thick as a silver dollar for use in Western States, so that the thickest coin in any pocket will not project above the top surface of end section 11.

End section 13 is provided with parallel cuts indicated at 17 and 18 that extend back to bend 15 and divide end section 13 into two side strips 19 and 20 and an intermediate strip or flap 21. Side strips 19 and 20 are disposed on opposite sides of the apertured portion of end section 11 and they are permanently glued or similarly affixed down on the adjacent top surface of end section 11, so that between them they provide a recess into which fits flap 21 when closed. The bend 15 serves as a hinge for flap 21. In effect permanently glued sections 11 and 12 and portions 19 and 20 provide a body having a recess at the bottom of which are disposed the coin receiving pockets and the flap fits into the recess to close the pockets and provide a flat packet.

Preferably the interior of flap 21 is provided along its three free edges with a band of adhesive 22 which when moistened will serve to hold flap 21 down in its recess. The coin holder is sold with adhesive band 22 dry and ready for use. The space bounded by adhesive band 22 may contain a printed order blank 23 glued or pasted to the under side of flap 21, and the parts are so located that the adhesive does not contact any of the coins.

In order to send coins by mail it is necessary only to moisten and press down flap 21 after insertion of the coins. The flap recesses into the assembly so that the closed holder is flat and of uniform thickness, and the coins are centrally disposed, being positively enclosed and protected on both sides by thick cardboard. No coins can slip out or be lost accidentally. Preferably the overall size of the folded assembly is such as to fit within a standard size of letter envelope.

Also is desired one or more paper bills or cur-

3

rency may be placed between the flap and the top surface of end section 11, the flap 21 and its associated recess being so large in area that the presence of even several thicknesses of bills will not noticeably interfere with flush fitting of the flap in its recess.

If desired flap 21 may be stapled to the body, as at 24, by means of an ordinary office stapling device, or a gummed flap extension might be provided on the free edge of flap 21 to overlie fold 14. These arrangements positively prevent the flap from becoming loose and absolutely maintain the currency and coins pocketed, so that large sums of money can be sent through the mails with reasonable safety and without the trouble of buying and selling money orders.

The invention may be embodied in other specific forms without departing from the spirit or essential characteristics thereof. The present embodiment is therefore to be considered in all respects as illustrative and not restrictive, the scope of the invention being indicated by the appended claim rather than by the foregoing description, and all changes which come within the meaning and range of equivalency of the claim are therefore intended to be embraced therein.

What is claimed and desired to be secured by United States Letters Patent is:

A rectangular uniformly flat coin holder comprising a flat section of cardboard formed inter-

4

mediate its sides with a plurality of coin receiving apertures, a second flat section of cardboard underlying said first section and comprising an extension of the first section folded back beneath and affixed to the undersurface of said first section, and a third section of cardboard comprising an extension of said second section folded along a fold line adjacent the free end of said first section and overlying the top surface of said first section, said third section having slits perpendicular to said fold line forming side portions permanently affixed to said first section on opposite sides of the area containing the coin apertures and an intermediate portion between the slits constituting a flap hinged at the fold line and provided with an adhesive coating whereby it is adapted to be adhesively secured to said first section so as to cover said coin receiving apertures.
